UNITED STATES PATENT OFFICE.

ALBERT N. FROST, OF VANCOUVER, BRITISH COLUMBIA, CANADA.

CAN OPENER.

Application filed November 25, 1927. Serial No. 235,610.

This invention relates to can openers. Its object is to provide a simple tool whereby a liquid container such as a sealed tin can of condensed milk may be instantly and easily pierced so that its contents may be available when poured from the aperture so made.

The tool consists of a stamping readily effected from a piece of suitable sheet metal which when folded over upon itself provides 10 two dependent tangs which hang over the edge of the container forming a gauge and an abutment for the punch itself, this latter being produced by a downwardly turned angular incision in the resilient portion of 15 the folded over portion so positioned that a smart blow upon it depresses the member and the sharp pointed angular projection thus piercing the container.

The drawings herewith forming a part of 20 the application show the details of the device more exactly. In these Fig. 1 is a view of the flat metal stamping. Fig. 2 is a side view of the device as completed and in the operative position on the top of a can or 25 container. Fig. 3 is a plan view from above, and Fig. 4 is a similar view from below.

In these drawings the numeral 5 indicates a can or container for condensed milk or the like, 6 a flat metal stamping formed with 30 the two projections 7 which when turned right-angularly to the surface of the stamping 6 form with the edge of the can a gauge or abutment at 8. The stamping is further incised at 9 and 10. The latter when also

turned right-angularly provides the spike 11 35 for piercing the cover or end of the can.

The extremity 12 of the stamping is folded over so that the spike 11 is positioned between the projecting tangs 7 as shown in Fig. 2, and the longitudinally central incision 9 is bent angularly to form the handle 13.

The operation of the device is obvious from the drawings. The tangs 7 are clipped over the edge of the can in the position indicated at 8 and held there by the handle 13, a smart blow is then given upon the folded member 12 by any handy hard object causing the spike to perforate the top of the can and the process repeated on the opposite edge to 50 form an air inlet.

Having now particularly described my invention, I declare that what I claim and desire to be protected in by Letters Patent, is:

A device for a can perforating tool comprising, a flat stamping of substantially rectangular elongated form and having one of its end bifurcated by the removal of a central U-shaped portion, an elongated U-shaped incision in the body of said flat stamping, the open end of the last said U-shape being adjacent the said bifurcation, and a second incision of substantially V-shaped form adjacent the end of the said stamping opposite the bifurcation.

In testimony whereof I affix my signature.

ALBERT N. FROST.
